Patented Aug. 1, 1922.

UNITED STATES PATENT OFFICE.

JOHN EDWARD ELDRIDGE, OF BUFFALO, NEW YORK.

BROOM.

1,424,241.

Specification of Letters Patent. Patented Aug. 1, 1922.

Application filed February 8, 1919. Serial No. 275,715.

To all whom it may concern:

Be it known that I, JOHN EDWARD ELDRIDGE, a citizen of the United States, residing in the city of Buffalo, in the county 5 of Erie and State of New York, have invented new and useful Improvements in Brooms, of which the following is a specification.

This invention relates to a broom in which 10 the handle is detachably connected with the brush. A broom of this character has many advantages over the ordinary broom in which the handle and brush are permanently connected, the chief advantage being that 15 such brooms may be boxed and shipped in knocked-down condition and therefore stowed more compactly than ordinary brooms, thereby economizing in space and effecting a saving in the cost of transportation. Such brooms will also effect a considerable 20 economy in materials inasmuch as a worn brush may be replaced by a new one and thus enable the same handle to be used repeatedly, thereby avoiding the waste incident 25 to the practice of throwing away the handle with the brush when the same are permanently connected.

It is the object of this invention to provide a broom in which the handle and brush 30 are detachably connected by means which are comparatively simple and inexpensive, which permit the handle and brush to be readily connected and disconnected either for use or for storing the same closely in a 35 box or crate for transportation, and which are strong and durable so that the same handle may be used repeatedly with many brushes.

In the accompanying drawings:

40 Figure 1 is a side elevation of a broom constructed in accordance with my invention. Figure 2 is a fragmentary sectional elevation showing the means for detachably connecting the handle and brush embodying, 45 my improvements. Figure 3 is a horizontal section taken on line 3—3, Fig. 2. Figures 4 and 5 are side elevations of the outer ferrule or socket of the brush viewed, respectively, from opposite sides thereof. Figure 50 6 is a similar view of the inner ferrule which is mounted on the handle and forms part of the means for detachably connecting the same with the brush.

Similar characters of reference refer to 55 like parts throughout the several views.

7 represents the brush of a broom which

may be constructed in any usual and well known manner of any suitable material such, for instance, as broom corn which is commonly employed for this purpose and 60 is the handle which is adapted to be detachably connected at its lower end with the upper end of the brush; this handle being preferably constructed of wood, as usual, although any other suitable material may be 65 employed if desired.

Within the upper end of the brush is arranged a socket or outer ferrule 9 which is preferably constructed of a sheet of metal bent into tubular form so that its longitudinal edges meet. These edges may be connected in any suitable manner, for instance, by means of electric welding or solder and the same are also preferably, though not necessarily, positively interlocked with each 70 other so that the same are held against lengthwise displacement relatively to each other. This last mentioned effect is preferably produced by providing one longitudinal edge of the outer ferrule with one or more 75 notches or recesses 10 and the other edge with one or more lugs or lips 11 which engage with the notches of the companion edge, as shown in Fig. 5. This outer ferrule has its lower part provided with a screw 80 thread 12 which is formed by stamping or otherwise while the upper part 13 of the same is unthreaded and of cylindrical form. The broom corn or other material forming the brush of the broom is secured to the 85 lower part of the outer ferrule or socket by placing this broom corn around this ferrule and tying or securing the same thereto by a binding wire 14 which is wound helically around the several layers or bunches of 90 broom corn in a manner similar to that now practised in manufacturing ordinary brooms. For this purpose the lower end of the binding wire is first connected with the lower part of the outer ferrule and then 95 wound around the upper parts of the broom corn as the same is applied successively around the outer ferrule after which the upper part of the binding wire is wound one or more times around the outer ferrule above 100 the brush and then secured to the adjacent upper part of the outer ferrule so as to prevent unwinding of this wire. For the purpose of finishing the broom at the upper end of the brush a strip 15 of suitable ornamental material, such for instance, as plush, 105 is tied around the upper contracted neck of

the brush by the winding of the binding wire.

Although various means may be employed for securing the upper and lower ends of the binding wire to the outer ferrule those which are shown in the drawings are preferred and consist of lower and upper hooks 16, 17 which are stamped outwardly from the sheet metal material from which the body of the 10 ferrule is made so that these hooks are formed integrally therewith. The lower end of the binding wire is engaged with the lower hook by twisting the same around the base of this hook preparatory to applying 15 the broom corn thereto and the upper end of the binding wire is secured in like manner to the upper hook after the operation of binding the broom corn is completed. In order to prevent the binding wire from becoming 20 detached from these hooks either during the process of manufacturing the broom or while the same is in use these hooks are so arranged that their mouths open circumferentially in opposite directions, each hook 25 projecting in a direction opposite to the direction of the pull of that end of the wire which is connected therewith.

The handle of the broom has its upper part 18 constructed of comparatively large 30 diameter while the lower extremity 19 thereof is reduced and a downwardly tapering conical shoulder 20 is formed between the lower reduced end and the upper enlarged part of the handle, as shown in Fig. 2. 35 Upon the reduced part of the handle is arranged an inner ferrule 21 which is made preferably of a sheet of metal bent into tubular form and having its longitudinal edges connected by electric welding or otherwise 40 and also preferably held against longitudinal displacement relatively to each other by means of one or more lugs or lips 22 arranged on one of these edges and engaging with corresponding notches or recesses 23 45 on the opposing longitudinal edge, as shown in Fig. 6. This inner ferrule is secured to the reduced part of the handle by means of nails 24, as shown by dotted lines in Fig. 2, or by any other suitable means and its upper 50 end is engaged with the tapering shoulder of the handle by the upwardly flaring upper end 25 of this inner ferrule as shown in Fig. 2. This inner ferrule is provided with a screw thread 26 which is formed thereon by 55 stamping or otherwise which thread is adapted to engage its exterior with the interior of the thread on the outer ferrule, and thereby form a detachable connection

between the handle and the brush of the broom. In the assembled condition of the 60 handle and the brush the upper edge of the outer ferrule engages with the upper part of the tapering shoulder of the handle, as shown in Fig. 2, so that this shoulder forms a stop which limits the entrance of the handle into the brush and also forms a flush or finished joint between the handle and the outer ferrule inasmuch as the same are of substantially the same external diameter and therefore reduce the liability of anything 70 catching on the broom while manipulating the same.

These means of detachably connecting the handle and brush of a broom are exceedingly simple and inexpensive in construction, the cost of manufacture being only slightly more than that of brooms in which the handle and brush are permanently connected with the added advantage, however, of permitting the brush and handle to be 75 taken apart and stowed much more compactly for transportation than is possible in the case of the ordinary brooms, thus securing the advantage of low cost of transportation, particularly when shipping 80 brooms for export in which case the charge for transportation is based on the cubical space which is occupied and not on the weight of the commodity. 85

Furthermore, a housekeeper need not purchase a new handle every time the brush is worn out inasmuch as the same handle can be used continuously with successive new brushes, and the store-keeper need not make as large an investment for keeping the required stock on hand inasmuch as he needs less handles in proportion to the number of brushes in order to meet the demands of his trade. These advantages are particularly desirable in the cotton and woolen mill districts where brooms are used very extensively and the cost is a considerable item. 90

I claim as my invention:

A broom and handle connection comprising an outer screw threaded ferrule connected to the broom, an inner screw threaded ferrule connected to the handle engaging with the inner side of said outer ferrule, and a handle having a reduced unthreaded lower part which engages with the inner ferrule 105 and an enlarged upper part which engages with said outer ferrule, said reduced and enlarged parts being integral and both removable from said broom. 110

JOHN EDWARD ELDRIDGE.
